Primary Examiner — Barbara Fox*Assistant Examiner* — Dana K Weiland(74) *Attorney, Agent, or Firm* — Brinks Gilson & Lione(57) **CLAIM**

I claim the ornamental design for a handheld terminal, as shown and described.

DESCRIPTION

FIG. 1 is a front perspective view of a handheld terminal of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof

The evenly spaced broken lines illustrate portions of the handheld terminal. The dot-dash broken lines illustrate limits of the claimed design. The broken lines form no part of the claimed design.
